REVERSE CURRENT TRIP CIRCUIT BREAKER

Charles L. Jones, Beaver, and Jerome Sandin, Pittsburgh, Pa., assignors to Westinghouse Electric Corporation, East Pittsburgh, Pa., a corporation of Pennsylvania

Application April 30, 1948, Serial No. 24,318

12 Claims. (Cl. 175—294)

1

This invention relates to circuit breakers, and more particularly to circuit breakers embodying electromagnetic tripping means for tripping the breaker in response to predetermined circuit conditions.

An object of the invention is to provide an enclosed multipole circuit interrupter with a reverse current relay which is mounted in one compartment of the casing where it is protected from damage and its line parts are enclosed, but is still easily accessible for inspection or replacement.

Another object of the invention is to provide a multipole circuit interrupter having main contact means with an improved reverse current relay which is provided with a potential coil, a solenoid energized upon operation of the relay in response to a reversal of current in the circuit interrupter to effect opening of the main contact means, the opening movement of the main contact means actuating a switch to effect deenergization of the potential coil.

Another object of the invention is to provide a two-pole circuit interrupter having a casing divided into three pole compartments, two of which are for receiving separable contact means and wherein an improved electroresponsive trip device is mounted in the third compartment in place of a third pole of the interrupter.

Another object of the invention is to provide a circuit interrupter with an improved reverse current relay having a normally energized holding coil and a solenoid energized upon operation of said relay to effect tripping of the interrupter in which the holding coil and the solenoid are energized from separate sources of energy.

The novel features that are considered characteristic of the invention are set forth in particular in the appended claims. The invention itself, however both as to structure and operation, together with additional advantages thereof will best be understood from the following detailed description thereof when read in conjunction with the accompanying drawings.

In said drawings:

Figure 1 is a top plan view of a circuit breaker embodying the principles of the invention, the cover being partly broken away to more clearly show the parts.

Fig. 2 is a vertical sectional view of the circuit breaker taken substantially on line II—II of Fig. 1.

Fig. 3 is a vertical sectional view taken on line III—III of Fig. 1 showing the reverse current trip device mounted in position in the breaker housing.

2

Fig. 4 is an enlarged top plan view of the reverse current trip device.

Fig. 5 is an enlarged sectional view taken on line V—V of Fig. 4 showing the reverse current trip device.

Figs. 6 and 7 are wiring diagrams of circuits for controlling the tripping of the breaker by the reverse current relay.

Referring to Figs. 1 and 2 of the drawings, the circuit breaker is of the multiple type and comprises a base 1 of molded insulating material suitably divided into three compartments, a cover 2 also of molded insulating material suitably secured to the base, operating mechanism indicated generally at 11, an overload trip device indicated generally at 13 having a separate electroresponsive tripping means for each of two poles of the breaker, a shunt trip device 12 and a reverse current relay indicated generally at 14. Each pole of the breaker is provided with a stationary contact 15 mounted on the lower end of a conductor 17 of the corresponding pole of the breaker, the conductor being suitably secured to the base 1 of the breaker.

The base 1 of the breaker is divided into three compartments by means of partition walls 31 molded integral with the base, and corresponding walls 39 molded integral with the cover 2.

The movable contact structures for the two poles of the breaker are alike; therefore, only the structure for the right-hand pole (Fig. 1) which is disposed in the center compartment will be described. A movable contact 18 is secured to a contact arm 21 which is loosely supported on a channel-shaped switch arm 23. The channel-shaped switch arms for the two poles are rigidly secured together for unitary movement by means of a tie bar 25 which extends transversely across all of the poles of the breaker. The tie bar 25 is secured to the switch arms 23 adjacent the pivoted ends thereof by means of metal clamps 27. An insulating tube 29 surrounds the tie bar in order to insulate the poles of the breaker. The channel-shaped switch arm 23 for the right-hand pole is pivotally supported on a pin 31 mounted in a U-shaped main frame 33 secured to the base 1 of the breaker by means of screws 35.

The upper end of a flexible conductor 45 is connected to the lower end of the contact arm 21 and the lower end of the flexible conductor is connected by means of a screw 49 to a conductor 51 which forms the energizing means for the corresponding pole of the trip device 13. The conductor 51 has its lower end connected to a terminal 53. The upper end of the conductor 17 is

similarly connected to a terminal connector. The circuit for each pole extends from the upper terminal 53, to the conductor 17, stationary and movable contacts 15-18, contact arm 21, flexible conductor 45, and the energizing conductor 51 to the lower terminal 53.

The movable contacts of the two poles of the breaker are adapted to be operated to open and closed positions to open and close the circuit through the breaker by the single operating mechanism 11. The operating mechanism comprises a releasable carrier or support member 59 pivotally mounted by means of a pin 61 on the main frame 33, a pair of toggle links 63 and 65 interconnecting the carrier 59 and the switch arm 23 for the right-hand pole, a U-shaped operating lever 67, overcenter springs 69 connecting the operating lever and the knee pivot pin 11 of the toggle links 63-65 and an insulating operating handle 73 for manually operating the lever 67.

The toggle link 63 is pivotally connected to the carrier 59 by means of a pin 75 and the toggle link 65 is similarly connected to the switch arm 23 for the right-hand pole by means of a pin 77. The two legs of the operating lever 67 are disposed adjacent the inner sides of the main frame 33 and are pivotally supported on pins 79 projecting inwardly from the sides of the frame. The operating handle 73 projects outwardly through an opening 81 in the cover 9 and is provided with an arcuate protective portion 83 having side portions 85 integral with the portions 83. The operating handle 73 is secured to the operating lever 67 by means of screws 87. The yoke portion of the operating lever 67 is provided with a formed over portion 89 for the purpose of engaging and resetting the carrier 59 following a tripping operation of the breaker. The carrier 59 is normally restrained in latched position (Fig. 2) by a latch 91 of the trip device, which engages a latching portion 93 of the carrier.

With the parts in the position shown in Fig. 1, the circuit breaker is manually operated to the "open" position by movement of the operating handle 73 and the operating lever 67 in a clockwise direction. During this clockwise rotation the line of action of the overcenter springs 69 moves below the pin 75 and causes the toggle links 63-65 to collapse, thereby causing movement of the switch arms 23 and the movable contacts 18 to the open-circuit position with a snap action. The breaker is closed by movement of the operating handle 73 in the opposite direction to the Fig. 1 position, during which movement the overcenter springs 69 move above the pivot pin 75 and move the toggle 63-65 to the in-toggle position to close the contact means with a snap action.

The circuit breaker is opened automatically, in response to an overload current occurring in the circuit of either pole of the breaker by operation of the trip device 13 which releases the latch 91. Release of the latch 91 frees the carrier 59 and permits the overcenter springs to rotate the carrier in a counterclockwise direction, thus causing collapse of the toggle 63-65 and movement of the switch arms to the open-circuit position. Following an automatic tripping operation, the breaker is reset and the contacts closed by first moving the operating handle 73 to the full open position to reset and relatch the carrier 59 with the latch 91, and then moving the handle 73 to the closed position to effect closing of the contacts.

The trip device comprises an insulating base or support member 95 (Fig. 2) suitably secured to an angle bracket 99 which, in turn, is secured to the base 1 of the breaker by means of the screws 49. The trip device is enclosed by a cover 100 of insulating material. The energizing conductor 51 for each pole has a loop 101 thereon which embraces the yoke 103 of a U-shaped magnet core 105 which is suitably secured by means of bolts 107 to the base 95 of the trip device. The bolts 107 extend through the pole pieces of the magnet core 105 and serve to slidably support on their lower ends an armature 109 which is biased to unattracted position by means of coil springs (not shown) surrounding the bolts 107 between the armature and the pole faces. The armature is supported in place by nuts on the lower ends of the bolts 107.

A trip bar 113, pivotally mounted on the base 95 of the trip device by pivot means (not shown) extends across all of the poles of the breaker. There is secured to the trip bar 113 a member 115 for each of the poles of the breaker, which member extends above the associated armature 109 to be operated thereby.

The latch 91 is pivotally mounted on a pin 117 supported in the brackets 99, and is biased in a counterclockwise direction by means of a spring (not shown). The lower end 119 of the latch member 91 comprises a latch surface which engages a latch roller 121 mounted on a bracket 123 secured to the trip bar 113.

Upon the occurrence of an overload current in the circuit through either pole of the breaker, the corresponding electromagnet is energized and attracts its armature 109. The armature engages the corresponding member 115 and rotates the trip bar 113 in a clockwise direction as viewed in Fig. 2. Clockwise rotation of the trip bar 113 moves the latch roller 121 out of engagement with the latch surface 119 of the latch member 91. The carrier member 59 is biased in a counterclockwise direction about its pivot 61 by the overcenter springs 69 so that when the latch member 91 is released, the carrier rotates the latch member 91 clockwise until the latching end 93 of the carrier 59 is free of the latch member 91. When the carrier 59 is thus released, the toggle 63-65 collapses and the movable contacts are moved to open circuit position. The breaker cannot be reclosed until the handle 73 has been moved to the full open position to reset and latch the carrier member. After the carrier 59 has been reset and latched, the operating handle may be moved to the closed position to effect closing of the contact means.

The reverse current relay 14 is disposed in the right-hand compartment of the base as shown in Fig. 1, and comprises a pair of spaced parallel U-shaped pole members 125 having an iron core 127 (Fig. 5) disposed therebetween adjacent one end. The core 127 is secured to the pole members 125 by means of screws 129 and has an insulating tube 131 surrounding it upon which is mounted a potential coil 133. Secured to the ends of the upper legs of the U-shaped pole members 125 is a T-shaped bracket 135 of non-magnetic material which has a downward extending leg 137 (more clearly shown in Fig. 5) for supporting a laminated armature 139. The armature 139 is pivotally mounted on a pivot stud 140 supported in the leg 137 and extending inwardly therefrom. The upper and lower legs of each of the pole members 125 are provided with pole faces 138 (Figs. 1, 4 and 5) for cooperating with the arma-

ture 139. The pole faces 138 are rigidly secured to the legs of the pole pieces adjacent the armature. Surrounding the armature 139 is an insulating tube 141 and a series coil 143 surrounds the tube 141. Insulating washers 145 are disposed adjacent the ends of the tube 141 between the series coil 143 and the legs of the pole members 125 to insulate the coil from the pole members.

The laminations of the armature are secured together by means of rivets 147, the upper two of which (Fig. 5) serve also to secure an angular bracket 149 to the armature adjacent the upper end thereof. One angle 151 of the bracket 149 extends to the right (Figs. 4 and 5) and carries a spring wire bridging contact 153 secured to the angle 151 by means of a rivet 155. Upon operation of the armature 139, the bridging contact 153 is adapted to bridge a pair of spaced stationary contacts 157 secured by means of screws 159 to an insulating plate 161. The plate 161 is mounted on the pole members 125 and is secured thereto by means of long screws 163 (Fig. 3) which extend through openings in the ends of the plate 161 and through openings in the pole members and threadedly engage metal inserts 165 molded in the base 7 of the breaker to rigidly secure the reverse current relay thereto.

The armature 139 is biased by means of a spring 167 against an adjustable limit stop screw 169 threadedly mounted in one of the pole members 125 as shown in Fig. 4 of the drawings. The ends of the spring 167 are hooked over spring studs 171 and 173, respectively, mounted in the end of the armature and in one of the pole members 125.

Referring particularly to Fig. 1 of the drawings, one end 175 of the series coil 143 is connected to a terminal connector 177 (see also Fig. 3) and the other end 179 is connected by means of a conductor 181 to the terminal connector 53 (see also Fig. 2) for the center pole of the breaker. An opening 182 is provided in the partition wall 39 of the cover to accommodate the conductor 181. The lower terminal 53 (Fig. 2) for the center pole of the breaker is connected by means of a conductor 183 to the lower terminal 185 (Figs. 1 and 3) for the right-hand pole. The circuit through the reverse current relay 14 and the center pole of the breaker extends as follows: From the terminal connector 177 (Figs. 1 and 3) through the series coil 143, conductor 181, terminal 53 for the right-hand pole, conductor 17 (Fig. 2), stationary and movable contacts 15-19, contact arm 21, flexible conductor 45, overload energizing loop 101, lower terminal 53 for the center pole and conductor 183 to the lower terminal 185 (Figs. 1 and 3) of the right-hand pole.

With normal rated current flowing in the proper direction through the circuit just described, the overload trip device will not function to trip the breaker and the armature 139 of the reverse current relay 14 will be attracted in a direction to maintain the bridging contact 153 in the open position as clearly shown in Fig. 4. The occurrence of an overload current in the circuit will cause the overload trip device 13 to function and trip the breaker in the previously described manner but will not affect the reverse current relay. Should a reversal of the direction of current flow occur, the armature 139 of the reverse current relay will be actuated to close the contacts 153-157 and energize the shunt trip device 12 over the circuit shown in Figs. 6 or 7 to trip the breaker.

The shunt trip device 12 (Figs. 1 and 3) comprises a solenoid 187 mounted on a bracket 189

secured to the base 95 of the overload trip device. The solenoid is provided with a movable core (not shown) having a plunger 191 attached thereto. The lower end of the plunger 191 is enlarged as at 193 and extends into a clearance opening 195 provided therefor in the base 95 of the trip device. The plunger 191 is adapted upon energization of the solenoid to engage and operate the trip bar 113 of the trip device.

10 Mounted on the upper end of the solenoid 187 (Figs. 1 and 3) is an insulating bracket 197 in which is rigidly secured a pair of spaced stationary contacts 199. A bridging contact 201 is loosely mounted adjacent the end of a rod 203 which is slidably supported in the bracket 197. The outer end of the rod 203 has an enlarged head as at 205 and the rod 203 is biased in a direction to engage the bridging contact by means of a coil spring 207 surrounding the rod 203 and compressed between the bracket 197 and the head 205 of the rod.

15 The contacts 199-201 are closed when the circuit breaker is closed but are adapted to be opened upon opening of the movable contacts of the circuit breaker by means of a channel-shaped arm 209. The arm 209 is secured to the tie bar 25 in the same manner as the channel-shaped switch arm 23 as shown in Fig. 2, that is, by means of clamps 27, and is insulated therefrom by the insulating tube 29.

20 Referring now to Fig. 6 of the drawings, the potential coil 133 is normally energized from a separate source over a circuit extending from a source conductor 211, the potential coil 133, contacts 199-201 (closed when the breaker is closed) to a source conductor 213. As long as the potential coil is energized and current of predetermined value is flowing in a predetermined direction through the series coil 143 and the circuit 25 of the right-hand pole of the breaker, the armature 139 of the reverse current relay 14 will be held in a position to maintain the contacts 153-157 open. If the direction of flow of the current through the series coil 143 of the reverse current relay is reversed, the polarity of the armature 139 is reversed, in which case the armature is actuated in a direction to close the contacts 153-157 and energize the shunt trip solenoid 187 over a circuit extending from the source conductor 211, contacts 153-157, the coil of the solenoid 187 to the source conductor 213.

25 Energization of the solenoid 187 causes actuation of the plunger 191 which engages and operates the trip bar 113 to release the latch 81 and thereby effect automatic opening of the breaker contacts. As the breaker contacts move to the open position, the arm 209 (Fig. 3) engages the rod 203 and moves it to effect opening of the contacts 199-201 which opens the circuit through the potential coil 133.

30 This permits the spring 167 (Figs. 1 and 4) to move the armature 139 back to its normal position opening the contacts 153-157 which de-energizes the solenoid 187. The breaker may now be reset and the contacts closed in the previously described manner.

35 A manually operable switch 215 may be provided if desired for closing contacts 217 which are connected in the circuit in parallel to the contacts 157. Operation of the switch 215, which may be located remotely from the circuit breaker, energizes the shunt trip solenoid to effect tripping the breaker open from a point remote from the breaker.

40 It will be observed that in the embodiment

shown in Fig. 6, both the potential coil 183 and the shunt trip coil 187 are arranged to be energized from a single source over the conductors 211-213. In some instances, it is preferable to energize the potential coil and the shunt trip device from separate sources. Accordingly, in the embodiment illustrated in Fig. 7, separate circuits are provided for the potential coil and the shunt tripping solenoid. The circuit for the potential coil 183 comprises source conductors 210 and 221 and extends from the conductor 210, through the potential coil 183, the contacts 199-201 to the source conductor 221. Similarly, the circuit for the solenoid 187 extends from a source conductor 223 through the contacts 153-157 and the solenoid 187 to a source conductor 225. The operation of the embodiment of Fig. 7 is the same as that described in connection with Fig. 6.

While the invention has been disclosed in accordance with the provisions of the patent statutes, it is to be understood that various changes in the structural details thereof may be made without departing from the spirit of the invention.

We claim as our invention

1. A multipole circuit interrupter comprising a casing section of one piece molded insulating material divided into a plurality of compartments extending longitudinally of said casing, a trip member extending transversely of said casing across all of said compartments and operable to effect automatic opening of said interrupter, support means for said trip member secured to said casing and forming a separate isolated compartment extending transversely of said casing, a trip device for at least one pole of said interrupter comprising an electromagnet mounted in said transverse compartment on said support means and operable in response to overload currents to actuate said trip member, electroresponsive means disposed in one of said longitudinal compartments and operable in response to a reversal of direction of current, a solenoid mounted in said one longitudinal compartment on said support means and operable when energized to actuate said trip member, and contact means actuated by said electroresponsive means for energizing said solenoid.

2. A multipole circuit interrupter comprising a casing section of one piece molded insulating material having partition walls forming a plurality of compartments extending longitudinally of said casing, separable main contact means disposed in at least two of said longitudinal compartments, a partition wall extending transversely of said casing forming a separate isolated compartment extending transversely of said casing adjacent one end thereof, a trip bar mounted on said transverse wall in said separate compartment, said trip bar extending across all of said longitudinal compartments and operable to effect automatic opening of said contact means, a trip device disposed in said transverse compartment comprising electromagnetic means for at least two poles of said interrupter operable in response to overload currents to actuate said trip bar, a solenoid disposed in the third of said longitudinal compartments operable when energized to actuate said trip bar, and electroresponsive means disposed in said third longitudinal compartment and operable in response to a reversal of the direction of flow of current through the circuit of one of said poles to effect energization of said solenoid.

3. A multipole circuit interrupter comprising a casing section of one piece molded insulating ma-

terial having partition walls molded integral therewith forming three compartments extending longitudinally of said casing, separable main contact means disposed in two of said longitudinal compartments, a member of insulating material secured to said casing and extending transversely thereof to form a separate transverse isolated compartment adjacent one end of said casing, a trip bar mounted on said transverse member disposed in said transverse compartment and extending across all of said longitudinal compartments, said trip bar being operable to effect automatic separation of said main contact means, trip means disposed in said transverse compartment and operable to actuate said trip bar in response to overload currents, electromagnetic trip means mounted on said transverse member and disposed in said third longitudinal compartment operable when energized to engage and actuate said trip bar, electroresponsive means including a normally energized potential coil disposed in said third longitudinal compartment adjacent the end of said casing opposite said transverse compartment, said electroresponsive means being operable in response to reversal of the direction of flow of current in one of the poles of the interrupter, contact means operable by said electroresponsive means for energizing said electromagnetic trip means, and auxiliary contact means operable upon separation of said main contact means to deenergize said potential coil.

4. A two-pole circuit interrupter comprising an enclosing casing having therein three compartments positioned side by side, separable main contacts and movable contact operating arms therefor in two of said compartments in said enclosing casing, an operating mechanism in at least one of said two compartments connected to said contact arms for actuating said contact arms to open and close said main contacts, a reverse current operated mechanism including a current coil positioned in the third of said compartments in said enclosing casing and connected to said operating mechanism to cause said operating mechanism to effect opening of said main contacts in the other two compartments in said enclosing casing, terminals at each of the opposite ends in two of said compartments, one terminal at one end of one compartment being connected to one end of said current coil, the other end of said current coil having a conducting strip extending into the adjacent compartment and connected to the main contact in said adjacent compartment.

5. A two-pole circuit interrupter comprising an enclosing casing having therein three compartments positioned side by side, separable main contacts and movable contacts operating arms therefor in two of said compartments in the enclosing casing, a manual operating mechanism in at least one of the two compartments having said main contacts and said contact arms therein connected to said contact arms for actuating said contact arms to open and close said main contacts, a tripping mechanism including a current traversed element positioned in the third of said compartments in the enclosing casing and connected to said operating mechanism to cause said operating mechanism to effect opening of said main contacts in the other two compartments, terminals at each of the opposite ends in two of the compartments, one terminal at one end of said third compartment being connected to one end of said current traversed element and the other end of said current traversed element

having a conducting strip extending into the adjacent compartment and connected to the main contact therein, and the other terminal in said third compartment having a conducting strip extending into the adjacent compartment and connected to said movable contact arm therein.

6. A two-pole circuit interrupter comprising an enclosing casing for a three-pole interrupter having three compartments therein positioned side by side, terminals at each of the opposite ends of two compartments, separable main contacts positioned in two of said compartments adjacent one end thereof, the main contacts in one of said two compartments being electrically connected to the terminal adjacent said one end of said compartment, movable contact operating arms in said two compartments in said enclosing casing, operating mechanism positioned in one of said two compartments adjacent the mid-portion thereof and connected to said contact arms for actuating said contact arms to open and close said main contacts, current responsive trip means in said one compartment electrically connected to the contact arm in said one compartment and connected to said operating mechanism to cause said operating mechanism to cause opening of said main contacts in said two compartments, said current responsive trip means being electrically connected to the other terminal in said one compartment, and a reverse current operated mechanism positioned in the third of said compartments in the enclosing casing and connected to the operating mechanism to cause said operating mechanism to cause opening of the main contacts in the other two compartments.

7. A two-pole circuit interrupter comprising a base and a cover each of insulating material forming an enclosing casing having therein three compartments positioned side by side, separable main contacts and movable contact operating arms therefor in two of said compartments in said enclosing casing, an operating mechanism in at least one of said two compartments connected to said contact arms for actuating said contact arms to open and close said main contacts, overload responsive means in each of said two compartments and electrically connected in series with said main contacts in said two compartments and acting on said operating mechanism to cause said operating mechanism to effect opening of said main contacts, a reverse current operated mechanism including a current coil positioned in the third of said compartments in said enclosing casing and electrically connected in series with the main contacts in one of said two compartments and said reverse current mechanism acting on said operating mechanism to cause said operating mechanism to effect opening of said main contacts in the other two compartments.

8. A multiple circuit interrupter comprising a casing of one-piece molded insulating material having partition walls forming compartments extending longitudinally of said casing, separable main contact means disposed in at least two of said compartments, a trip bar extending across said compartments and operable to effect automatic opening of said contact means, a trip device comprising an electromagnet for at least one pole of said interrupter disposed in one end of said casing and operable in response to overload currents to actuate said trip bar, support means for said trip device rigidly mounted on

said casing and forming a separate compartment for said trip device, said separate compartment extending transversely of said longitudinal compartments adjacent one end of said casing, electroresponsive means disposed in one of said longitudinal compartments adjacent the opposite end of said casing, said electroresponsive means being operable in response to reversal of the direction of flow of the current in the circuit of said one pole, and a solenoid mounted in said one longitudinal compartment on said support means for said trip device to be energized in response to operation of said electroresponsive means and operable when energized to actuate 15 said trip bar.

9. A multipole circuit interrupter comprising a casing of one-piece molded insulating material having partition walls extending substantially the length of said casing forming isolated compartments, separable main contact means disposed in at least two of said compartments, a trip member extending across said compartments and operable to effect automatic separation of said contact means, trip means 20 electrically connected in series relation with the main contacts in each of at least two of said compartments, said trip means being operable in response to overload currents to actuate said trip member, support means for said 25 trip means mounted on said casing, a relay disposed in one of said compartments and operable in response to reversal of flow of current in the circuit controlled by said interrupter, said relay comprising an energizing winding 30 connected in series relation in the circuit controlled by one pole of the breaker, a normally energized holding coil and an armature, a solenoid mounted in said one compartment on said support means adjacent said trip member and operable when energized to engage and actuate 35 said trip member, switch means operable by said armature to effect energization of said solenoid, and auxiliary contacts operable upon separation of said main contact means to effect 40 deenergization of said holding coil.

10. A multipole circuit interrupter comprising a casing of molded insulating material having partition walls forming three compartments, main stationary contact means disposed in two of said compartments, pivoted movable contacts in said two compartments cooperating with said main stationary contacts, a pivot common to said movable contacts and extending into the third compartment, a trip member 45 extending across all of said compartments and operable to effect automatic opening movement of said movable contacts, a relay disposed in said third compartment and operable in response to reversal of flow of current in the 50 circuit controlled by said interrupter, said relay comprising an energizing winding connected in series relation in the circuit of one pole of the breaker, potential coil and an armature, a solenoid disposed in said third compartment adjacent said trip member operable when energized to actuate said trip member, and a first switch means operable by said armature to effect energization of said solenoid, a second switch means positioned in said third compartment connected in series relation with said potential coil, and means in said third compartment mounted on said pivot and movable with 55 said movable contacts in said two compartments when said contact means moves to open 60 70 75

said circuit to engage and open said second switch means.

11. A multipole circuit interrupter comprising a casing of molded insulating material having partition walls forming three separate compartments, main stationary contact means and cooperating movable contact means disposed in two of said compartments, a trip member disposed adjacent one end of said casing extending across said compartments and operable to effect opening movement of said movable contact means, an electromagnetic trip device electrically connected in series relation with the main contacts in one of said two compartments and operable in response to overload currents to actuate said trip member, an electroresponsive relay disposed in the third one of said compartments, said relay being connected in series with the main contacts in said one compartment and operable in response to reversal of the direction of current flow in the circuit controlled by said interrupter, said relay including a normally energized potential coil, an armature operable by said trip device, a solenoid disposed in said third compartment adjacent said trip member operable when energized to actuate said trip member, spring contact means mounted on said armature for effecting energization of said solenoid upon operation of said armature, switch means disposed in said third compartment connected in series relation with said potential coil, and means extending into said third compartment and operable upon opening movement of said movable contact means to actuate said switch means to cause deenergization of said potential coil.

12. A multipole circuit interrupter comprising a casing of one-piece molded insulating material having partition walls forming compartments positioned side by side, separable main contact means disposed in two of said compartments, a trip member extending transversely across said compartments adjacent one end of said casing and operable to effect auto-

matic separation of said main contact means, trip means disposed on one side of said trip member operable in response to overload currents to actuate said trip member, electroresponsive means including a normally energized potential coil removably mounted in one of said compartments adjacent the other end of said casing, a tripping solenoid removably mounted in said one compartment adjacent to but on the opposite side of said trip member from said trip means operable when energized to actuate said trip member, a movable armature having switch means thereon operable by said electroresponsive means in response to a reversal of direction of flow of the current in the circuit controlled by the interrupter to effect energization of said solenoid, and auxiliary contact means in said one compartment operable upon separation of said main contact means to deenergize said potential coil.
